UNITED STATES PATENT OFFICE.

HENRY C. OSBORN, OF CLEVELAND, OHIO, ASSIGNOR TO THE AMERICAN MULTIGRAPH COMPANY, OF CLEVELAND, OHIO, A CORPORATION OF OHIO.

PRINTING MACHINE HAVING A CHANGEABLE FORM.

Application filed November 27, 1926. Serial No. 151,091.

This invention relates to a machine for printing with a form periodically changed, coupled with mechanism for keeping a record of the matter changed. The invention 5 may for example be used for printing a list of addresses corresponding to the addresses successively printed on individual mail matter.

I have shown the invention embodied in 10 a machine adapted to list the printed items on a continuous strip of paper fed from a roll. I have satisfactorily used such an embodiment for example, for printing and listing the amounts and names of the payees of 15 checks. Such machine is very useful for printing dividend checks, where the name and amount are likely to recur at successive periods.

My invention is hereinafter more fully 20 explained in connection with the drawings and the essential novel features are summarized in the claims.

In the drawings Fig. 1 is a vertical transverse section through a machine embodying 25 my invention; Fig. 2 is a longitudinally vertical section substantially on the plane indicated by the offset line 2—2 on Fig. 1; Fig. 3 is a transverse vertical section on a plane indicated by the line 3—3 on Fig. 2 30 looking in the opposite direction to Fig. 1; Fig. 4 is an approximately horizontal section through the luster platen and an adjacent portion of the machine, as indicated by the line 4—4 on Fig. 1; Fig. 5 is a horizontal section through the supply roll and the takeup roll of the luster attachment, as 35 indicated by the offset line 5—5 on Fig. 1; Fig. 6 is a perspective of a portion of the printing drum; Fig. 7 is a face view of an 40 illustrative check adapted to be filled in with this machine. The remaining figures illustrate a modification. Fig. 8 is a sectional elevation on a plane similar to Fig. 1; Fig. 9 is a horizontal section on the line 9—9 of 45 Fig. 8; Fig. 10 is a sectional side elevation of gearing for the platen drive, looking in the same direction as Fig. 3; Fig. 11 is a perspective of one of the members of the clutch for the luster platen; Fig. 12 is a detail in edge view of the clutch controlling 50 lever.

That portion of the mechanism shown which prints the check, envelope or card, for example, consists of a multigraph having a 55 changeable form slidably mounted on its pe-

riphery after the manner of application No. 11,224 filed Apr. 7, 1926, by John H. Hult, and assigned to my assignee, The American Multigraph Co. Briefly such printing mechanism may be described as follows: 60

Vertical frame plates 10 and 11 connected by a base portion 12 constitute the frame of the machine. In the plates 10 and 11 is mounted a rotatable main shaft, shown as driven by a crank 15. On this main shaft 65 is a skeleton drum consisting of disc-like end members 16 and 17 and a removable partly cylindrical segment 18 mounted thereon. The drawings show the segment as held in place by spring hooks 19 engaging the 70 shaft 14.

One portion of the multiple form in the drawings comprises a printing blanket 20 hooked at one end to a fixed longitudinal bar 21, and at the other end to a movable 75 bar 22, which is mounted on a member 23 movably clamping the shaft 14 and pressed away from the edge of the segment by a jamb screw 25. Another portion of the 80 form is a similar but smaller blanket 26 anchored to a fixed bar 27 and to a bar 28 hinged to the segment and pressed away from it by screw 29. As shown in Figs. 1 and 6 the blankets 20 and 26 are sheet metal 85 plates having rows of upstanding projections 38 carrying removable embossed strips 39.

A third portion of the form, as shown, 90 comprises a removable plate 30 of trough shape, carrying the changeable portion of 95 the form and slidably mounted in ways provided by the bars 21 and 27 and resting on an intermediate portion 31 of the segment. This plate is adapted to be slid into place in its ways endwise of the machine 95 (from the left hand of Fig. 2), against an abutment 40, which is pressed outwardly by a spring 41. A finger latch 42 spring 100 pressed radially outward is adapted to engage the outer end of the plate and retain it in mounted position against the pressure of the spring 41. When, however, the finger latch is pressed inwardly the plate is released and the spring 41 ejects it sufficiently for the operator to grasp it and 105 remove it entirely.

The changeable plate shown corresponds to that shown and claimed in my prior applications Nos. 106,792 and 128,760, filed May 5th, 1926 and Aug. 12th, 1926, respectively. 110

As there shown, the plate has longitudinal corrugations 35, carrying overhanging lips 36, and embossed printing strips 37 surmounting these corrugations and having inwardly flanged edges extending beneath the lips. The blankets 20 and 26 may be formed in a somewhat similar manner.

The end members 16 and 17 of the drum carry ribbon spools 50 from which an inking ribbon 51 extends about the entire form from one spool to the other. A drum so equipped is adapted to print on paper passed between it and a roller platen 60, shown as mounted beneath it and geared to it. The roller platen is preferably mounted on a shaft 61 eccentrically mounted in adjustable bearings, and the gearing for driving the platen may comprise a gear 65 on the drum, a meshing gear 66 on the platen, 20 and an Oldham coupling connecting the gear 66 with the platen. Suitable feed rolls 70, Fig. 1, may control the feed in any well-known manner. This view illustrates also at 71 a suitable ejecting roll. Fig. 3 indicates at 72 gearing for driving the ejecting roll from the gear 65 and at 75 gearing for driving the under feed roll from the platen gear 66.

Such mechanism as described is adapted, 30 for example, for filling in check blanks fed between the drum and platen. The small blanket 26 may readily carry the check number and date, while the amount of the check and name of the payee may be carried by 35 the changeable plate 30. In operation the drum is given successive rotations always in the same direction, a new plate 30 being substituted at the end of each rotation. In filling in checks the blanket 20 may be idle, 40 as shown, or by means of the two blankets the entire check may be printed by this machine if desired. For other uses, the fixed and changeable parts of the form may be made up in a great variety of ways, 45 according to the imprints and lists desired.

To keep a list of the names and addresses of the payees and the amounts of various checks—thus illustrating the listing operation—I provide the lister mechanism in two forms, one shown particularly in Figs. 1, 3, 4 and 5, and the other in Figs. 8 to 12 inclusive. The first form will now be described.

Secured to the rear edges of the frame plates 10 and 11 are brackets 80 and 81. In these brackets are mounted adjustable bearings 82 and 83, in which is eccentrically mounted a shaft 84 carrying a roller 85 with a soft platen surface 86 positioned to coat 60 with the plate 30 when it comes opposite the platen.

Behind the lister platen 86, mounted in the brackets 80 and 81, is a stationary rod 90 on which is a spool 91 carrying a supply 65 roll 92 of paper. The strip of paper passes

from the under side of this roll 92 beneath the platen 86 and upwardly on the forward face thereof and behind a guide rod 100 to a receiving spool 101 mounted on a shaft 103 and adapted to be turned by it. This shaft is journaled on bearing pins 104, 105 carried by the brackets 80 and 81, and is provided with a gear 107 which is connected by an idler 108 with a gear 88 on the shaft 84, which carries the lister platen. This gear 88 is connected by a flexible coupling with this platen, and meshes with the gear 65 on the drum.

It follows from the construction described that as the multigraph drum is rotated the lister attachment is idle until the plate 30 comes into coaction with the platen 86; then this platen, coacting with the printing form on the plate, not only causes printing on the strip 92, but feeds it upwardly at the same time, the excess of paper being taken up by the spool 101 frictionally driven by the shaft 103. Except when the plate 30 is opposite the platen 86, the rotation of the platen does not feed the paper, by reason of a tension on the supply roll, nor is the friction drive sufficient to turn the spool 101. I will now explain this more in detail with reference to Fig. 5.

The supply roll shaft 90 is a stationary rod having flattened end portions 110 removably occupying vertical slots in the frame members 80 and 81. This rod is surrounded by a bushing 112, which makes an abutment for an end disk 113 for the spool 91. At the other end of the spool is slidably mounted a disk 115 pressed toward the spool by a compression spool 116, which surrounds the rod and thrusts against a collar 117 adjustably clamped on the rod 90 by set screw 118. By adjusting the position of the collar, the braking action against rotation of the supply roll of paper is adjusted, so that the platen 86 will not normally feed the paper. A light spring 122 allows the shaft 103 to revolve idly within the spool 101. When, however, the plate 30 comes opposite the platen and the paper is gripped between them, it is thereby fed upwardly, and then the light spring 122 rotates the spool 121 sufficiently to cause it to wind in the freed portion of the paper.

Fig. 7 indicates at A a bank check adapted to be filled in by this machine. In the particular arrangement of printing forms illustrated, the matter on the check with the exception of the changeable portions is supposed to be printed at some preceding time. The check number a and the date a^1 may be readily inserted by the strips 39 on the small blanket 26. The amount of the check and the name of the address and payee, shown at a^2 and a^3 may all be supplied by embossed printing strips 37 on the plate 30.

The blanket 26 is shown as located longi-

tudinally beyond and offset from the platen 86. Thus there is no coaction between them. The entire fill-in matter in the plate 30, however, is printed on the paper strip 92. 5 It is desirable to leave a short blank space on this paper strip between successive items printed. I have found that notwithstanding the positive feed caused by the engagement of the plate printing strips with the 10 platen, momentum gives the strip a slight additional feed and provides the desired space between the successive imprints on the prints. This space may be reduced by increasing the pressure of the brake spring 116, or increased by weakening this pressure, 15 according to the adjustment of the collar 117.

Sometimes it is desirable to list matter on only short strips of paper, the same being 20 torn off from the rest of the strip instead of being rolled up on the takeup spool. For such purpose, I provide a fork 125 which may be carried on the frame plate 80. The ribbon may be threaded through this fork 25 as illustrated at 92^a in Fig. 1 and dropped down behind the supply roll, and then at any time the end portion of the strip may be torn off by using the upper tine of the fork as a knife edge.

30 For many uses of my invention it may be desired to print matter by the drum and main platen, which is not so positioned as to avoid coming opposite the lister platen. The blanket 20 provides for mounting such 35 additional printing matter in various positions on the drum. In cases where the matter is intended for use with other matters circumferentially registering with the changeable form I substitute for the constantly driven cylindrical lister platen, a 40 periodically driven segmental platen. Such segmental platen is normally away from the printing drum and has no coaction with the matter on the blanket which may move past such platen, but, at the desired time, an adjustable cam on the drum may operate to 45 throw in a clutch connecting the segmental platen with the drum, so that it will then rotate and coact with the matter on the changeable plate to print such matter. The 50 modification, Figs. 8-12, illustrates such construction and operation and will now be described.

Fig. 8 shows the segmental lister platen 130 in its active position; it is normally idle and in a position distant from the drum. This platen is loose on the shaft 131 but may be driven by a gear 132 loose on the bearing stud 133 and meshing with the gear 65 on the drum. The platen is connectable for rotation with the gear 132 by a single rotation clutch designated 140 as a whole.

60 One member of the clutch 140 consists of a disc 141 rigid with the gear 132 and shown 65 as pinned to a hub of the gear. Another

member consists of the disc 142 rigid with the platen. A third member comprises an intermediate disc 143 having radial ribs 144 occupying corresponding grooves in the disc 142 after the manner of an Oldham coupling. 70 The final member of the clutch comprises a locking pin 145 adapted to lock the members 141 and 143 together, this locking pin being slidably mounted in the member 141 and adapted to engage a notch 148 in the member 143. The pin 145 normally held withdrawn by a lever 150 positioned by a spring 151 but operated at the proper time by a cam 152 adjustably positioned on the drum, engaging a roller 153 on the lever. 75 80

With the construction just described, as the changeable form on the drum is coming into position adjacent the platen 130, the cam 152 engages the roller 153 and operates the trip lever 150 to free the pin 145, thereupon, a spring 149 seats the pin in the notch 148, engaging the clutch. The platen 130 now makes one complete rotation at the same peripheral speed as the drum and thus the matter on the changeable plate is printed 85 on the listing strip. This same printing operates to feed the strip upwardly and the frictional take-up roll heretofore described may wind in the printed portion. At the end of the rotation the head on the pin 145 90 engages the beveled end 154 (Fig. 12) of the lever and withdraws itself, thus opening the clutch.

95 A suitable brake is supplied for the segmental platen which furnishes a constant 100 friction, sufficient to stop the platen immediately when the clutch pin is withdrawn but not sufficient to add a material load to the drive when the clutch is engaged. As shown in Fig. 9, this brake comprises a 105 non-rotatable disc 160 slidably mounted on a supporting stud 161 and pressed by springs 162 against a leather washer 164 between the disc and the adjacent end of the platen.

110 By employing this normally inactive segmental platen controlled by a clutch under the control of an adjustable cam on the drum, I may mount on the drum by means of a blanket 20 matter circumferentially registering with the changeable form. Such 115 employment therefore increases the range of use of the machine over the simpler form first described.

120 It will be seen that my lister attachment does not interfere with normally printing action of the multigraph machine. It is adapted for mounting on frame plates of an addressing multigraph and cooperates with it without change in the multigraph. The listing attachment is very simple in construction, and experience has demonstrated that it is very effective in keeping a record of the changeable matter printed. This record is very useful not only of such 125 work of keeping track of the addresses and 130

amounts of checks or bills, but may advantageously be used for example in keeping a list of addresses of the individuals to whom addressed circulars are sent, thus aiding materially in a follow-up system. If the address plates are arranged alphabetically in the original receptacle, the list will be correspondingly alphabetical, and thus a permanent record obtained in which every name may be readily located.

I claim:

1. The combination of a printing member, a set of mutually independent address plates adapted to be individually mounted thereon successively, a roller platen adapted to coat therewith, a second roller platen adapted to coat with the same address plates while on the printing member, and means for holding a roll of paper passing between the second platen and the form.
2. The combination of a rotary drum, a set of mutually independent address plates adapted to be mounted in any order one after the other on the drum, two rotary platens coating with the address plate, and means for holding a roll of paper with paper passing from the roll between the second platen and address plate.
3. The combination of a rotary drum, a longitudinal slideway in the surface thereof, open at one end, a series of changeable forms, any one of which may be slid longitudinally into place in the slideway on the drum, a rotary platen coating with the form, a second platen adapted to coat with the form, and means for passing paper between the drum and second platen without discharging it, whereby successive imprints may be made on the same piece.
4. The combination of a rotary drum, a longitudinal slideway in the surface thereof, open at one end, a series of changeable forms, any one of which may be slid longitudinally into place in the slideway on the drum, a rotary platen coating with the form, an inking ribbon mounted on the drum and extending across the form, a second platen adapted to coat with the form, and means for passing a continuous strip of paper between the form and second platen and retaining it for a subsequent impression.
5. The combination of a rotary drum, a longitudinal slideway in the surface thereof, open at one end, a series of changeable forms, any one of which may be slid longitudinally into place in the slideway on the drum, a rotary platen coating with the form, an inking ribbon mounted on the drum and extending across the form, a second platen adapted to coat with the form, means for holding a roll of paper, and means for feeding paper therefrom between the drum and platen.
6. The combination of a rotary printing

drum, a platen coating therewith, a second platen coating with the drum, a spool carrying a roll of paper which passes between the second platen and drum, a brake retarding the unwinding of the spool, and a series of address plates slidably mounted one at a time on the drum and adapted to coat with both platens.

7. The combination of a rotary drum, a roller platen coating therewith, a longitudinal slideway on the drum for receiving individual address plates, a second platen adapted to coat with the address plates whereby a second impression may be made by the plate without changing its position on the drum, a roll of paper threaded between the drum and second platen, a take-up roll for said paper, means for frictionally driving the take-up roll and an adjustable brake on the supply roll.

8. The combination of a rotary printing drum, a series of address plates adapted to be selectively mounted thereon, two roller platens coating therewith, means for feeding sheets of paper between the drum and one of the platens, a spool adapted to carry a roll of paper from which the strip passes between the drum and the other platen, a spool for winding in the paper after leaving the drum and latter platen, a spring brake on the supply roll, a spring friction drive for the take-up roll, the spring applying the friction for the take-up being materially lighter than the brake spring on the supply roll.

9. The combination of a rotary printing drum having on its surface a longitudinal slideway parallel with the axis, a series of address plates any of which may be mounted in said slideway, a roller platen beneath the drum, a second roller platen behind the drum, means for supporting a roll of paper at the rear of the second platen, the paper passing from said roll onto the underside of the second platen and thence upwardly between it and the drum, an adjustable brake on the supply roll, and means for causing rotation of the second platen consequent upon the rotation of the drum.

10. The combination of a rotary printing drum having on its surface a longitudinal slideway parallel with the axis, a series of address plates any of which may be mounted in said slideway, a roller platen beneath the drum, a second roller platen behind the drum, an inking ribbon mounted on the drum and passing across the address plate, means for supporting a roll of paper, at the rear of the second platen, the paper passing from said roll onto the underside of the second platen and thence upwardly between it and the drum, a take-up roll for said strip of paper after it leaves the second platen, a friction drive for the take-up roll geared with the drum, a fork behind the take-up

roll through which paper may be threaded instead of wound onto the take-up roll, and means for causing the rotation of the second platen consequent upon the rotation of the 5 drum.

11. The combination of a rotary drum, a changeable form thereon adapted to make an impression, a set of different forms individually and indiscriminately installable 10 thereon and removable therefrom for each impression, means for holding a continuous strip of paper, and means for making successive impressions on such strip corresponding to successive imprints on different sheets. 15

12. The combination of a rotary drum adapted to carry a changeable form, means for printing thereby, a set of different forms individually and indiscriminately installable 20 thereon and removable therefrom for each impression, means carrying a roll of paper, means for causing an additional impression from said form on paper from said roll, and means for winding in the paper from the 25 roll after the same is printed.

13. The combination of a printing mem-

ber, a set of different forms individually and indiscriminately installable thereon and removable therefrom for each impression, a rotary platen coacting with said form, a second rotary platen, and means for supporting a continuous strip of paper passing between the second platen and the form to receive successive imprints on the same strip for successive printing on different sheets on the 30 35 first platen.

14. The combination of a rotary printing drum, a roller platen coacting with the drum for only a portion of the cycle of operation to effect printing, a spool adapted to carry 40 a roll of paper from which the strip passes between the drum and platen, a spool for winding in the paper after leaving the drum and platen, a brake on the supply roll and a constantly acting friction drive from the 45 drum for the take-up roll, the frictional connection for the take-up being materially lighter than the brake on the supply roll.

In testimony whereof, I hereunto affix my signature.

HENRY C. OSBORN.
